UNITED STATES PATENT OFFICE.

EDDY T. THOMAS, OF NEW YORK, N. Y.

SEWING-MACHINE.

SPECIFICATION forming part of Letters Patent No. 242,284, dated May 31, 1881.

Application filed November 19, 1880. (No model.)

To all whom it may concern:

Be it known that I, EDDY T. THOMAS, of the city, county, and State of New York, have invented an Improved Sewing-Machine, of which the following description, in connection with the accompanying drawings, is a specification.

This invention relates to sewing-machines employing an eye-pointed needle and shuttle; and my invention comprehends improvements in devices for moving the shuttle and four-motioned feeding device from a single eccentric on the needle-bar-operating shaft by connecting mechanism, as will be hereinafter described. The shuttle-carrier rock-shaft is made available as the shaft by which to actuate two independent cams, one of which lifts the feed-bar and permits it to fall at the proper times, while the other moves the feed-bar forward, a spring retracting the said bar. In this my invention these two cams are connected by a pin or stud on one entering a slot in the other cam, the said slot being sufficiently larger than the diameter of the pin to permit more or less lost motion between the cams, so as to enable them to operate the feed in the proper sequence as to time.

In another application, No. 20,838, filed by me November 19, 1880, for United States Patent, I have shown a single cam-block for moving the feed-bar.

Figure 1 represents, in vertical section, a sufficient portion of a sewing-machine to illustrate my invention, the parts omitted from the drawings being supposed to be common. Fig. 2 is a section of Fig. 1 on the line $x^1 x^2$, the frame being broken out to show the feed-operating spring. Fig. 3 is a longitudinal vertical section on the line $x^3 x^4$, Fig. 1. Fig. 4 is a section of Fig. 3 on the dotted line $x^5 x^6$, the said figure showing the cam d in section, and part of the cam c at the rear of it through the opening 6 of cam d , the foot of lug c^4 being cut off to show the lower end of c^3 beyond it. Fig. 4^a is a section on line $x^7 x^8$ of Fig. 2. Fig. 5 is a detail showing the connecting-rod depending from the upper rotary shaft; Fig. 6, details of the feed-bar; Fig. 7, an enlarged side view of the two feed-operating cams in the position they will occupy after the feed-bar has been raised and is beginning to move forward. Fig. 8 represents, in detail, face views of the feed-

operating cams in the positions they will occupy when the feed-bar is retracted and lowered; Fig. 9, details of the same when the feed-bar is first lifted; Fig. 10, details of the same after the feed-bar has been moved forward; Fig. 11, details of the same when the feed-bar is beginning to fall on its backward movement; Fig. 12, details showing, in top view and section, the cam for moving the feed-bar forward; Fig. 13, a top view of the feed-bar-lifting cam and its pin to engage and turn the cam to move the feed-bar forward. Fig. 14 represents, in elevation and partial section, a modified plan for actuating the feed-cams; Fig. 15, a section of Fig. 14 on the dotted line $x^9 x^{10}$, and Figs. 16 to 21 are details of the feed-cams in different positions.

The frame-work, including the cloth-plate a and overhanging arm a' and the rotating needle-bar-actuating shaft a^2 , are and may be all as usual. The shaft a^2 has an eccentric, a^3 , about which is placed the eccentric strap a^4 of the link a^5 , connected at its lower end with the ball a^6 on a pin, a^8 , located at one end of the bell-crank lever a^7 , pivoted at a^9 , and joined by the connecting-rod a^{10} with an arm of the vertically-placed vibrating shuttle-carrying lever b , secured to a rock-shaft, b' , the shuttle (not shown) to be moved by the said shuttle-carrying lever, having its face against the smooth wall b^2 , which latter will be provided with the usual groove to receive the needle and permit the loop of its thread to be thrown out in position to be caught by the point of the shuttle. The rock-shaft b' , (see Fig. 3,) having at one end a head, is entered loosely through the cam c , which is to move forward the feed-bar c' , slotted to receive the guiding and supporting pin c^2 ; thence through the cam d , which will be fixed to the shaft, and which will lift the feed-bar and permit it to fall at the proper times; thence, also, loosely through the bearing e , and into a hole in the shuttle-carrier, to which it is fixed by a pin, b^3 , or otherwise. The cam c , provided with a side incline, 2, (shown fully in Figs. 7 to 12, inclusive,) and placed loosely on the rock-shaft b' , has applied to it a friction brake or device, c^5 , (shown in Fig. 4,) to keep the said cam c at rest, except when positively turned by the pin 3, projected from the cam d into the slot 4 in the hub of

the cam *c*. (See Figs. 2 and 7.) This slot-and-pin connection enables the cam *d*, fixed on the shaft *b'*, to first move and act on the leg *c⁴* of the feed-bar, to raise or permit it to be lowered before the inclined surface 2 of cam *c* commences to act upon the leg *c³* of the feed-bar to move it forward, or to permit the feed-bar to be moved backward by the spring *c²* on the pin 10, (see Fig. 2,) which acts to press the feed-bar backward after its usual serrated surface has dropped from contact with the fabric. The rock-shaft *b'*, being fixed with relation to the shuttle-carrier and loose in the bearing *e*, is made to turn the cams *d* and *c* at the proper times to impart to the feed-bar its usual four motions.

Fig. 8 shows the cams *c d* in the positions they will occupy when the feed-bar is down and retracted. By the time the cam *d* reaches the position Fig. 9 it will have lifted the serrated part of the feed-bar in contact with the fabric, and then the incline 2 of cam *c* will commence to act on the leg *c³* and move the feed-bar forward, and with it the fabric, the feed-bar being kept lifted by resting on the cam *d*, as in Fig. 10. The feed having taken place the rock-shaft is reversed, carrying with it the cam *d*, the pin 3 of the said cam moving in the slot 4 of cam *c*, while the latter is held by the friction device *c⁵*, the cam *d* at that time moving in the direction of the arrow next to it in Fig. 11, and as soon as the leg *c⁴* enters the notch 6 the pin 3 takes hold of and turns the cam *c*, changing the position of its incline 2 so that the spring *c²* is free to move the feed-bar backward.

In another application, filed by me on the 19th day of November, 1880, I have shown another plan for moving the feed from a rock-shaft set in motion by the shuttle-carrier in its vibrations.

Referring to the modification, Figs. 14 to 21, it will be noticed that the shuttle-carrier is attached to a tubular shaft, *f*, which carries the cam *d*, and that the cam *c* is connected with a shaft, *g*, having a crank, *g'*, provided with a pin, *3^x*, like pin 3 before referred to, said pin *3^x* entering a slot, *4^x*, (see Fig. 15,) in the

shuttle-carrier. The friction device *c⁵* in this modification is attached directly to the cam *d*. 50

The shuttle-carrier, deriving its vibration from the connecting-rod *a⁹*, moves with it the tubular shaft and cam *d* to lift the feed, as described of the cam *d*, before referred to, and at each vibration the shuttle-carrier at the ends of the slot *4^x* strikes the pin *3^x* extended therein, and turns the shaft *g* and the cam *c* to move the feed-bar forward, as described of cam *c*, before referred to.

I claim—

1. The shuttle-carrier, its connected rock-shaft, and means to vibrate the shuttle-carrier and oscillate the rock-shaft with it, combined with the feed-bar and two independent cams on the said rock-shaft, one fast thereon to 65 raise the feed-bar and permit it to fall, and the other loose thereon and moving the feed-bar forward at the proper times, substantially as described.

2. In a sewing-machine, the feed-bar having 70 two projections or legs, and the two independent cams, one provided with a pin and the other with a slot, whereby one cam is made available to move the other, as described, one cam moving the feed-bar forward, while the 75 other raises it preparatory to or as it is being moved forward, and permit it to fall at the proper time, combined with the rock-shaft, means to move it, and a suitable friction device to retard the movement of one of the said 80 cams, substantially as set forth.

3. In a sewing-machine, the rotating shaft *a²* in the overhanging arm, its eccentric *a³*, the link *a⁵*, the elbow-lever *a⁷*, link *a⁹*, vibrating shuttle-carrier *b*, the shaft *b'* rocked by it, and 85 the feed-bar, combined with the two independent cams *c d*, the one loose and the other fixed upon the said rock-shaft, and connected together by a pin-and-slot connection, all substantially as described.

In testimony whereof I have signed my name to this specification in the presence of two subscribing witnesses.
